UNITED STATES PATENT OFFICE.

ALEXANDRE ALPHONSE ROYAU, OF CHÂTILLON-SOUS-BAGNEUX, NEAR PARIS, FRANCE.

CANDLE-MOLDING MACHINE.

SPECIFICATION forming part of Letters Patent No. 475,521, dated May 24, 1892.

Application filed September 10, 1891. Serial No. 405,250. (No model.)

To all whom it may concern:

Be it known that I, ALEXANDRE ALPHONSE ROYAU, of the city of Châtillon-Sous-Bag-
neux, near Paris, France, have invented an
5 Improved Candle-Molding Machine, of which
the following is a full, clear, and exact de-
scription.

Candle-molding machines usually necessi-
tate considerable labor and are slow in opera-
10 tion.

15 This invention relates to an improved ma-
chine for molding candles which, notwith-
standing its relatively small dimensions, is
capable of a considerable output with little
labor—say of turning out two hundred and
20 fifty candles every quarter of an hour when
worked by one man only.

Reference is to be had to the accompanying
drawings, forming part of this specification,
25 wherein—

Figure 1 is a side elevation of a candle-
molding machine embodying my improve-
ment. Fig. 2 is an end elevation of the same.
25 Fig. 3 is a vertical section of the mold-chest
and candle-sheaths, showing the candle in
the mold. Fig. 4 is a similar view showing
the candle in the sheath. Fig. 5 is a similar
30 view, the candle being in the sheath and the
piston-rod drawn down, leaving the mold
ready for another filling. Fig. 6 is a top plan
view of Fig. 3. Fig. 7 is an enlarged central
vertical section of a candle-sheath with the
35 holding-flap closed down. Fig. 8 is a similar
view, the flap being thrown up. Fig. 9 is a
cross-section on line 9 9, Fig. 7. Fig. 10 is an
enlarged longitudinal and cross section of a
40 multiple supply-cock, and Fig. 11 shows the
mechanism for discharging the candles from
the molds.

45 The principal characteristic of the machine
is the rapidity with which either hot or cold
water can be introduced into the mold-chest.
In order to instantly fill the mold-chest with
water at the desired moment, the following ar-
rangement is employed:

The machine comprises two parts symmet-
rically arranged, as shown in Fig. 2, each con-
sisting of a mold-box *a*, combined with a sys-
tem of pipes for the supply of water thereto.

50 At the upper part of the machine-frame are
mounted two tanks *b* for supplying water to

the two mold-chests. In order to admit water
around the whole of the molds *c* at once, a se-
ries of pipes *d* connect each reservoir *b* with
the cylindrical casing *e* of a multiple-way 55
cock *e'*, extending the whole length of the
machine, the hollow plug *f* of which is made
in two parts and operated from opposite ends
to avoid torsion thereof, as shown in Fig. 10.
From the casing *e* extend as many pipes *g* as 60
there are transverse rows of molds in the
chest, all controlled by the plug *f*, the water,
if cold, serving to cool them suddenly for dis-
charging the molded candles, or if hot to heat
the molds, as required. The water contained 65
in the separate reservoirs *b* passes through
pipes *d*, casing *e*, cocks *e'*, and pipes *g*, con-
nected to the mold-chests, and thence around
the molds *c*, Figs. 3, 4, and 5.

In order that the water, whether cold or hot, 70
shall reach the molds at the required tempera-
ture, the latter are inclosed concentrically in
tubes *h*, having an intervening annular space
to contain the water. All the tubes *h* are fixed
15 to a plate *i*, as shown in Figs. 3, 4, and 5, so
that the water arriving by the pipes *g* is first
distributed over the plate *i* and then descends
through the tubes *h* around the molds, and
finally escapes through the slits *k* at the lower
20 part of tubes *h* into the mold-chest *a*, from
which it is drawn off by a cock *l*, Fig. 2.

Upon a longitudinal plate *m*, Figs. 1 and 11,
are mounted as many -shaped brackets *n*
as there are molds, forming a row in the lon-
gitudinal direction, to which brackets *n* are 85
connected as many tubular piston-rods *o* as
there are molds in the transverse direction,
the ends of the plate *m* resting upon arms *p*,
Figs. 1 and 11, provided with a guide-collar *q*,
sliding on a vertical guide-rod *r*, mounted be- 90
tween two cross-pieces *s*, Fig. 2.

At each end of the machine a cross-head *t*
works in guides and is moved up and down
by means of a screw-shaft *u*, operated by a
pair of bevel-pinions *v* and winch-handle *x*, 95
these cross-heads *t* serving to elevate the
plates *m* and rods *o* for discharging the molds.
The cross-heads *t* may be made to lift either
one or both plates *m*, according as the molds
of one or both chests are to be discharged at 100
one time. For this purpose the said cross-
heads *t* are connected with the plates *m*, to be

lifted by means of latches *y*, which are caused to engage with lugs *z* on the guide-collars *q*, as shown in Fig. 11.

After the molds are filled the layer of wax in the mold-trough is removed, for which purpose the side 1, Figs. 1 to 5, of the trough is turned down on its hinge 2 and the wax cut off flush with the molds. The cross-heads *t* are then raised so as to force up all the piston-rods *o* and push the molded candles into the sheaths 3. (Represented in Figs. 3, 4, 5, 7, 8, and 9.) The candles on entering these sheaths raise forked spring-flaps 4, as shown in Fig. 4, which come beneath and retain the candles, the sheaths 3 holding the candles a sufficient time to give time for the spring-flaps to engage beneath them. The sheaths are mounted in series upon forks 5, which rest on a bar 6, extending within the whole length of the mold-chest. After the candles have been raised into the sheaths 3 the rods *o* are again lowered by moving down the cross-bars *m*, after which a fresh quantity of wax is run in before cutting the wicks of the previous batch of candles contained in sheaths 3, in order to keep the wicks stretched and central in the molds *c*. The wicks *w* are drawn from a reel or other suitable device through an opening in the side of the tubular rods *o*, and thence through the vertical center of the molds *c*, as shown in Figs. 3 and 5. When the finished candle has passed into the sheaths at the top of the mold, the wick is cut at the lower or tapering portion of the candle and the candle can then be removed from the sheaths. As the rods or pistons *o* descend they leave the molds free and clear for the reception of another charge of candle-stock.

By surrounding the candle-molds with an annular chamber to receive the water from the tanks on top of the machine the candle-molds can be kept at any temperature desired,

the liquid being enabled to pass from the annular chamber through openings in the bottom of the surrounding tube, into and out of the mold-chamber, as heretofore described.

It is evident that the form of the tanks *b*, the number of pipes *g*, and molds *c*, &c., as well as the dimensions of the various parts, may be considerably varied without departing from the nature of the invention.

I claim—

1. In a candle-molding machine, a heating and cooling apparatus combining therein a candle-mold chest, candle-molds secured in said chest, tubes surrounding said molds and adapted to form a chamber between said tubes and molds, a chamber *a* around and above said tube-chambers and connected therewith, water-tanks arranged above said chamber *a*, pipes connecting said tanks with said chamber *a* and the top of said tube-chambers and adapted to instantly fill said tube-chambers, and means for discharging the water from and out of the mold-chest, all said parts being arranged and adapted to operate substantially as described, and for the purposes set forth.

2. In a candle-molding machine, the combination, with the molding and discharging mechanism, of a holding mechanism consisting of receiving sheaths or tubes 3, secured to the top of the molding-machine, and a spring holding-flap 4, pivoted to one side of said sheaths and adapted to hold the candle as it passes from the mold, substantially as described, and for the purposes set forth.

The foregoing specification of my improved candle-molding machine signed by me this 19th day of August, 1891.

ALEXANDRE ALPHONSE ROYAU.
